UNITED STATES PATENT OFFICE.

WILLIAM A. LORENZ, OF HARTFORD, CONNECTICUT, ASSIGNOR, BY MESNE ASSIGNMENTS, TO THE NOISELESS TYPEWRITER COMPANY, OF MIDDLETOWN, CONNECTICUT.

TYPE-WRITING MACHINE.

1,046,205.

Specification of Letters Patent. Patented Dec. 3, 1912.

Application filed April 16, 1909. Serial No. 490,208.

To all whom it may concern:

Be it known that I, WILLIAM A. LORENZ, a citizen of the United States, residing at Hartford, in the county of Hartford and 5 State of Connecticut, have invented certain new and useful Improvements in Type-Writing Machines, of which the following is a full, clear, and exact description, such as will enable others skilled in the art to 10 which it appertains to make and use the same.

This invention relates to typewriting machines, and one of the objects thereof is to provide new and improved means for arresting 15 in a silent manner the movements of the various operative parts thereof.

Another object is to provide improved mechanism designed to reduce to a minimum impact or concussion of the moving parts 20 during the operation of the machine.

Other objects will be in part obvious and in part pointed out hereinafter.

The invention accordingly consists in the features of construction, combinations of elements and arrangement of parts which will 25 be exemplified in the construction herein-after set forth, and the scope of the application of which will be indicated in the following claims.

30 In the accompanying drawings, wherein is illustrated several of various possible embodiments of my invention, Figure 1 is a vertical, sectional view taken through a portion of the machine, showing a key lever and universal bar with the present invention applied thereto; Fig. 2 is a similar view showing the position of the parts when the key lever is depressed; Fig. 3 shows a different embodiment of the stop mechanism; Fig. 40 4 is a plan view and Fig. 5 is a side view partly in section showing the stop mechanism adapted to the marginal stop block for arresting the return movement of the carriage; and Fig. 6 is a sectional view upon an 45 enlarged scale showing the stop device applied to a marginal stop block.

Similar reference characters refer to similar parts throughout the several views of the drawings.

50 Referring now to the drawings, 1 represents the frame of the machine, 2 a universal bar shaft carrying rocker arms 3, said arms in turn supporting rods 4 whose lower ends are interposed in the support of a universal 55 bar 5. The universal bar in the present in-

stance is provided with a cushion 6 upon which rests the several key levers, one of which is shown at 7 pivoted upon a bar 8 and held upwardly as by means of a spring 9.

10 represents a rod or link which is adapted to be connected to the type bar action (not shown) and 11 represents a pad which engages the key levers upon their upward stroke and arrests them in the position 65 shown in Fig. 1.

To the lower part of the universal bar is attached a guide plate 12 provided with an aperture 13 for receiving a post 14 extending upwardly from a portion of the frame 70 of the machine indicated at 15, said post being vertically adjustable by means of a screw 16 tapped to the frame. After adjustment said post may be secured in position, as by means of the lock nut 17 threaded upon the 75 lower end thereof. The post 14 is provided with a collar 18 and seated upon this collar is a relatively heavy coil spring 20. Upon this coil spring in the present instance is positioned a collar 21 which supports a 80 lighter coil spring 22 whose upper end engages the plate 12 of the universal bar.

In the position of Fig. 1 the parts are resting in their normal position, the coil springs 20 and 22 supporting the universal 85 bar in its upper position. By moving the universal bar 5 downwardly, as when a key lever is depressed to the position shown in Fig. 2, the coil spring 22 will be first depressed until the coils meet for the greater 90 portion of the stroke, but during the compression of spring 22 the spring 20 being stronger will be compressed a distance only equal to the resistance offered by the spring 22. Then during the remaining portion of the downward stroke of the key lever and the universal bar the spring 20 will also be compressed either partially or fully, offering great resistance to the stopping of the 95 parts. During the closing of the spring 22 100 no appreciable noise will be made, because that spring strikes no solid obstruction by reason of the fact that the heavy spring yields slightly, and when the heavier spring 20 is compressed no appreciable noise will 105 be produced because the distance that spring moves in order to be compressed is so slight that its collapsible effect is silent. The distance through which the spring 22 will be compressed will be equal to the aggregate 110

distance between the individual coils, and the universal bar will be moved through a space equal to this distance plus the distance through which the heavier spring 20 5 yields under compression.

In the embodiment of the invention shown in Fig. 3 of the drawings 23 indicates an adjustable screw threaded in the frame 15, said screw being adapted to be held in any 10 adjustable position by means of a lock nut 24. A single compressible coil spring 27 is placed between the cupped portion 25 of screw 23 and a cup 26 depending from the universal bar. The coils of this spring vary 15 in cross-section, the spring being thin, as at 28, and thicker at the other end, as at 29. In the present instance the coils are shown to increase gradually in thickness. If desired, however, the coils may be all of one 20 thickness for a portion of the length of the spring and then thinner for a greater length thereof, whereby the structure will approximate the light and heavy springs, as shown in the embodiment illustrated in Fig. 1.

25 In the embodiment of the invention illustrated in Figs. 4, 5 and 6 the double coil springs are carried in a marginal stop block 30 which is adjustable upon a margin rack 31 supported upon the carriage 32. 33 represents the center tie of the machine and 34 represents the marginal lever which can be shifted outwardly for overwriting through suitable connection operable at the keyboard.

35 Referring to Fig. 6 the marginal block 30 is shown in section carrying a slide 35 having a head 36 and the stop pin 37 which engages the end 38 of a slot 40 in the block 30 and which limits the outward movement 40 of the slide. A light coil spring 41 and a heavier coil spring 42 are inserted in the block behind the slide 35, and act to press said slide outwardly as shown. A collar 43 may be interposed between the two springs 45 and a similar collar 44 may be employed at the end of spring against which an adjustable screw 45 may bear, said screw being adapted for varying the endwise position of the collar 44 thus adjusting the tension of 50 the springs. In the operation of this embodiment of the invention, whenever the carriage returns the slide head 36 will strike the margin lever 34, compressing springs 41 and 42 against the collar 44. The first 55 part of the compressing movement will be easily effected owing to the light tensional strength of the spring 41 and the last part thereof will be resisted by means of the heavier coil spring 42. In this manner the 60 return of the carriage is cushioned and the shock of the parts gradually reduced.

It will accordingly be seen that I have provided a construction well adapted to attain among others all the ends and objects 65 above pointed out in a simple yet efficient

manner. The elimination of concussion or impact between the moving parts insures a silent operation. The construction described in each of the above embodiments is such that little resistance will be offered to the movement of the movable part during the greater portion of its movement, the arresting operation taking place only during the latter portion of such movement and is effected without the production of noise. As will be obvious this spring construction may be employed in any other relation desired in a type-writing machine, wherein it is desired to effect a noiseless arresting of the parts.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following 90 claims is intended to cover all of the generic and specific features of the invention herein described, and all statements of the scope of the invention which, as a matter of language, might be said to fall therebetween.

Having described my invention, what I claim as new and desire to secure by Letters Patent is:

1. In a typewriting machine, the combination with a universal bar and the key levers which rest thereon, of means for gradually and silently arresting the downward movement of the key levers without impact or concussion, comprising a fixed support, a post mounted thereon and projecting into said universal bar, and a spring coiled about said post and interposed between the universal bar and said fixed support.

2. In a typewriting machine, the combination with a universal bar and the key levers co-acting therewith, of means for gradually and silently arresting the movement of said parts without impact or concussion, comprising a fixed support, a post mounted thereon and projecting into said bar when depressed, and spring means coiled about said post and interposed between the universal bar and said support.

3. In a typewriting machine, the combination with a universal bar and the key levers co-acting therewith, of means for gradually and silently arresting the movement of said parts without impact or concussion, comprising a fixed support, a post mounted thereon and projecting into said bar when depressed, and spring means comprising a plurality of parts of varying cross sectional area interposed between the universal bar and said fixed support.

4. In a typewriting machine, the combination with a universal bar and the key levers co-acting therewith, of means for gradually and silently arresting the movement of said parts without impact or concussion, comprising a fixed support, a post mounted thereon and projecting into said bar when depressed, spring means coiled about said post and interposed between the universal bar and said support, and means for changing the relative position of said spring means to alter the path of travel of said movable part.
5. In a typewriting machine, the combination with a universal bar and the key levers co-acting therewith, of means for gradually and silently arresting the movement of said parts without impact or concussion, comprising a fixed support, a post mounted thereon and projecting into said bar when depressed, spring means coiled about said post and interposed between the universal bar and said support, means for changing the relative position of said spring means to alter the path of travel of said movable part, said post being threadedly connected with said fixed part, and means whereby the same may be turned to change the relative position of said spring means.
6. In a typewriting machine, the combination with a universal bar and a fixed support, of means for gradually and silently arresting the movement of said universal bar without impact or concussion comprising a post secured to one of said parts, the other of said parts having an opening through which said post is adapted to pass when the universal bar is actuated, and spring means associated with said post adapted to be interposed between the universal bar and said fixed support.
7. In a typewriting machine, the combination with a universal bar and a fixed support, of means for gradually and silently arresting the movement of said universal
- bar without impact or concussion comprising a post secured to one of said parts, the other of said parts having an opening through which said post is adapted to pass when the universal bar is actuated, spring means associated with said post adapted to be interposed between the universal bar and said fixed support, and means for changing the relative position of said spring means.
8. In a typewriting machine, the combination with a universal bar and a fixed support, of means for gradually and silently arresting the movement of said universal bar without impact or concussion comprising a post secured to one of said parts, the other of said parts having an opening through which said post is adapted to pass when the universal bar is actuated, and spring means having one end of larger cross-sectional area than the other coiled about said post and interposed between the universal bar and said fixed support.
9. In a typewriting machine, the combination with a universal bar and a fixed support, of means for gradually and silently arresting the movement of said universal bar without impact or concussion comprising a post secured to one of said parts, the other of said parts having an opening through which said post is adapted to pass when the universal bar is actuated, a spring means composed of two parts of different cross sectional area coiled about said post and interposed between the universal bar and said fixed support, and means for changing the relative position of said spring means.

In testimony whereof I affix my signature, in the presence of two witnesses.

WILLIAM A. LORENZ.
